ATTORNEYS

UNITED STATES PATENT OFFICE.

FREDERICK J. PROBST, OF NEW YORK, N. Y.

DESIGN FOR A BOTTLE.

No. 39,385.

Specification for Design.

Patented June 30, 1908.

Application filed May 16, 1908. Serial No. 433,324. Term of patent 14 years.

To all whom it may concern:

Be it known that I, FREDERICK J. PROBST, a citizen of the United States, residing at the city of New York, borough of Brooklyn, in the county of Kings and State of New York, have invented a new, original, and ornamental Design for Bottles, of which the following is a specification, reference being had to the accompanying drawing, forming part thereof.

The figure is an elevation of a bottle showing my new design.

I claim:

The ornamental design for a bottle, as shown.

FREDERICK J. PROBST.
